(57) CLAIM

The package design with surface ornamentation, as shown and described.

DESCRIPTION

FIG. 1 is a perspective view of a package design with surface ornamentation embodying the new design as shown, wherein the grayscale shaded regions are regions of color;

FIG. 2 is a front view thereof;

FIG. 3 is a right side view thereof;

FIG. 4 is a back view thereof;

FIG. 5 is a left side view thereof;

FIG. 6 is a top view thereof;

FIG. 7 is a bottom view thereof;

FIG. 8 is a perspective view of a second embodiment of a package design with surface ornamentation embodying the new design as shown, wherein the grayscale shaded regions are regions of color;

FIG. 9 is a front view thereof;

FIG. 10 is a right side view thereof;

FIG. 11 is a back view thereof;

FIG. 12 is a left side view thereof;

FIG. 13 is a top view thereof; and,

FIG. 14 is a bottom view thereof.

Broken lines shown in the figures described above are for illustrative purposes only and form no part of the claimed design.
